APPARATUS FOR INCINERATING MATERIAL

Roger Granger, Brooklyn, N. Y.

Application August 19, 1936, Serial No. 96,741

1 Claim. (Cl. 110—14)

This invention relates to apparatus for incinerating material, such as sewage.

More specifically stated, the invention relates to apparatus for disposing of sewage screenings and sludge cake. The disposal of such matter constitutes a very serious problem in large cities and involves an enormous expense. Sometimes such material is towed out to sea and dumped, thus polluting the coastal waters. It has been proposed to convert the material into fertilizer, but this has been found to be too expensive to be practical.

The burning of sewage screenings and sludge cake presents unusual problems due to the relatively large water content even after a part of the water has been removed by vacuum filters and other means. Unless the temperatures in the various parts of the apparatus are properly regulated and controlled the outer layer of the material will be closed or sealed with the moisture confined therein. Furthermore, it has been found that for proper and efficient incineration the temperature at the receiving end of the apparatus should be relatively low and the material should be gradually fed through the apparatus and kept in motion, being subjected to increasing temperatures until it is burned to ash.

This invention has for one of its objects to provide apparatus for so burning or incinerating sewage screenings or like material that the final product will be in the form of ash easily disposed of and no objectionable gases will be released to the atmosphere.

Another object of the invention is to provide apparatus of the character described so designed that the hot exhaust gases can be utilized to heat the air which enters the intake end of the apparatus into which is fed the material to be incinerated.

Another object of the invention is to provide apparatus of the character described so designed that the noxious gases from the burning material or sewage will pass through the lower drum and be burned therein, any unburned gases passing outwardly through the stack.

Another object of the invention is to provide apparatus of the character described, so constructed that means is provided for removing residual ash from the gases passing out of the stack.

Further objects of the invention will appear from the following specification taken in connection with the drawing which forms a part of this application, and in which

Fig. 1 is a vertical sectional elevation illus-

trating apparatus constructed in accordance with the invention;

Fig. 2 is a vertical sectional elevation taken substantially on line 2—2 and illustrating the outlet passages for the burned gases and the 5 passages through which the intake air is conducted and preheated; and

Fig. 3 is a detail sectional view showing the gas washer.

The invention briefly described consists of incinerating apparatus particularly designed for burning and disposing of sewage screenings and sludge cake. The apparatus comprises upper and lower rotatable drums, the material being conducted to the inlet end of the upper drum, 15 through said drum, and thence into the inlet end of the lower drum and through the lower drum, the ash or residue dropping into an ash pit at the outlet end of the lower drum and the hot gases passing from the outlet end of the 20 lower drum upwardly through passages which surround air inlet conduits or passages and thus heat the air which is fed into the inlet end of the upper drum.

Heating means, such as an oil burner, is provided at the inlet end of the lower drum and heats and burns the material which has been gradually raised in temperature during its passage through the upper drum. The two drums as shown are oppositely inclined relative to each 30 other and lifts are provided to lift the material during the rotation of the drums and during the passage of the material therethrough so as to permit the air and hot gases to have access to the material and thus release the gases from 35 the material being burned and cause a maximum amount thereof to be consumed.

Means is provided in connection with the stack to prevent fine ash from being discharged from the stack, this means comprising a gas washer. 40

Further details of the invention will appear from the following description.

In the particular embodiment of the invention illustrated in the drawing, the apparatus comprises a pair of drums A and B which are supported at the ends on suitable rollers 10. The upper drum is supported on frame work 11 and the lower drum on frames 12. The two drums are positively rotated by means of suitable driving mechanism consisting of motors 15 which are connected through gears 16 and 17 to shafts 18 on which are mounted gears 19 which mesh with gears 20 carried by the drums. 45 50

Each of the drums is provided on its inner surface with a plurality of longitudinally extending 55

radially disposed baffles or lifts 21 which cause the material passing through the drum to be lifted and dropped during its passage, thus breaking up the material and permitting the air and hot gases to permeate the material, dry and burn it.

The lower drum B is provided with a lining 22 of firebrick or other suitable heat insulating material.

10 The drum A is not submitted to as high temperatures as the drum B and therefore is not provided with a lining.

15 The outlet end of the drum A and the inlet end of the drum B are disposed in and communicate with a chamber 25. A ledge or inclined shelf 26 is formed in this chamber intermediate the upper and lower portions thereof and deflects the material discharged from the drum A into the inlet end of the drum B. The lower portion of the 20 chamber 25 is provided with heating means, such as an oil burner 27, the blast or flame of this burner being directed into the inlet end of the drum B.

25 At the outlet end of the drum B the incinerator has formed therein an ash pit 28 and a conduit 29 which communicates with a stack 30. A door 33 is provided in the ash pit 28 for removing the ashes. A gate 24 is provided for closing the passage into the pit when the door 33 is open.

30 Means is provided in the stack 30 for heating the intake air for the drum A and from the showing in Fig. 2 it will be noted that the stack has formed therein vertical passages 31 for the hot gases received from the drum B and also 35 has formed therein passages 32 which are disposed in heat exchange relation to the passages 31. The passages 32 have formed therein baffles 33 for deflecting the air which is forced therethrough by a fan 34 which discharges the air into the passages 32 through a conduit 35.

35 The air passages 32 communicate with an intake conduit 40 which conducts the preheated air to the inlet end of the drum A.

40 The material to be incinerated, such for instance, as sewage screenings, is collected in a tank or drum T and is pumped therefrom by an injector R to a hopper H. The hopper discharges the material into a casing 45 in which is mounted an endless belt 46 supported on hexagonal drums 50 or pulleys 47. The right hand pulley 47 viewing Fig. 1 is driven in the following manner: Shaft 48 of the pulley 47 has mounted thereon a gear 49 which meshes with a gear 50 mounted on a shaft 51. Gear 50 in turn meshes with a gear 52 mounted on a shaft 53 which is driven by a belt 54 which engages a pulley 55 mounted on the shaft 53 and a pulley 56 mounted on a shaft 57 of a motor M.

45 The belt 46 passes between upper and lower sets of presser rolls 58 and 59 which squeeze the material and remove a considerable portion of the water therefrom. It is desirable that sludge, before incineration, be passed through a vacuum filter prior to feeding the material to the incinerator, so that a portion of the water may be extracted therefrom.

50 The discharge end of the belt 46 delivers the material to a chute 60 through which it is deposited on a table or shelf 61. Sludge cake from a vacuum filter may be fed into the chute 60 by a conveyer 46'.

55 A plunger 62 is slidably mounted on the table or support 61 and is connected by a link 63 to a lever 64 mounted on a fixed pivot 65. The lever 70 75 64 is connected intermediate its ends at 66 to a

link 67, the other end of which is connected to a crank arm 68 on a shaft 69 of a motor 70.

5 In order to prevent material being fed from the chute 60 when the plunger 62 is retracted, a stop plate 71 is connected to the shelf or table 61 and slides through slots in the chute 60 at the discharge end of the conduit or chute 60, closing the chute when the shelf 61 is retracted. The stop plate 71 thus acts as a slide valve. The plunger 62 acts as a pusher to feed the material along the table or support 61 and into the drum A.

10 In order to prevent fine ash from passing out through the stack a gas washer is provided, through which the gas can be by-passed. This construction is shown particularly in Fig. 3. The 15 washer comprises a casing 75 having a chamber communicating with the stack 30 through inlet and outlet conduits 76 and 77. A water conduit 78 conducts water to the chamber and discharges the water through spray nozzles 79. Baffles 80 20 are disposed below the nozzles and baffles 81 are disposed above the nozzles to intercept any ash or material in the outgoing gas. A fan 82 is mounted in the outlet conduit 77 and draws the gases through the chamber and forces it through the 25 conduit 77 into the stack.

25 If desired, the amount of gas by-passed through the washer can be regulated by a butterfly valve 85 mounted in the stack. If this valve is closed all the gas will be drawn through the 30 washer.

The water and residue ash flows out of the chamber through an outlet pipe 86.

Operation

35

The apparatus above described operates as follows: The material to be incinerated is fed into the receiving end of the drum A by the reciprocating feed table or shelf 61 and gradually passes from the receiving end to the discharge end of the drum A, which as shown in Fig. 1, is inclined 40 downwardly from the receiving to the discharge ends thereof. Preheated air enters the drum A through the conduit 40, this air having been heated by the hot gases discharged from the drum B. 45

During its passage through the drum A the material is lifted and dropped and the hot air is permitted to permeate the material which is thus broken up and the moisture content is materially reduced.

50 From the drum A the material drops downwardly and is deflected by the shelf 26 into the inlet end of the drum B where it meets the hot blast of the oil burner 27 and is heated and burned during its passage from the inlet end to the discharge end of the drum B. During its passage through the drum B the material is also lifted and dropped and broken up, the gas being freed therefrom, a part of the gas being burned and the remainder passing outwardly through the 55 passage 29 into the stack.

55 The ash resulting from the burned material drops into the ash pit 28 and can be removed therefrom.

60 From the description in the preceding paragraphs it will be obvious that the draft or direction of flow of the hot air and gases in this apparatus is through the upper drum from the inlet to the outlet end thereof and through the lower drum from the inlet to the discharge end thereof. Thus, the noxious gases from the sewage screenings or other material pass from the drum A into the drum B and in the drum B are burned to a large extent. Any unburned gases 65 pass into the stack.

75

The air fed to the upper drum A is preheated by the gases in the stack and this hot air heats and dries the material passing through the drum and materially reduces the moisture content.

5 Any fine ash passing into the stack is removed by the gas washer and the valve 85 can be adjusted to regulate the passage of gas through the washer.

10 From the foregoing specification it will be evident that a simple, practical and efficient incinerator has been designed and that by means of this apparatus a maximum quantity of material 15 can be disposed of at a minimum cost.

15 Although one specific embodiment of the invention has been particularly shown and described, it will be understood that the invention is capable of modification and that changes in the construction and in the arrangement of the various cooperating parts may be made without departing from the spirit or scope of the invention, 20 as expressed in the following claim.

What I claim is:

Apparatus of the character described comprising a pair of oppositely inclined rotatable drums disposed one above the other, means for rotating said drums, a chamber communicating with the outlet end of the upper drum and the inlet end of the lower drum, heating means at the inlet end of the lower drum arranged to direct a blast of heat on the material as it passes from the outlet end of the upper drum into the inlet end of the lower drum, a stack communicating with and disposed at the outlet end of the lower drum, means for conducting material to the inlet end of the upper drum, means for conducting the material from the outlet end of the upper drum to the inlet end of the lower drum, and means located in heat exchange relation to said stack for conducting hot air to the inlet end of the upper drum.

ROGER GRANGER. 20
